B. BOWLER.
ARTIFICIAL HAND.
APPLICATION FILED FEB. 25, 1919.

Patented Apr. 22, 1919.

UNITED STATES PATENT OFFICE.

BARTHOLOMEW BOWLER, OF TORONTO, ONTARIO, CANADA.

ARTIFICIAL HAND.

1,301,367.

Specification of Letters Patent. Patented Apr. 22, 1919.

Application filed February 25, 1919. Serial No. 279,069.

To all whom it may concern:

Be it known that I, BARTHOLOMEW BOWLER, of the city of Toronto, in the county of York, Province of Ontario, Canada, a subject of the King of Great Britain, have invented certain new and useful Improvements in Artificial Hands, of which the following is a specification.

This invention relates to the hand shown and described in my prior United States application No. 277,818, dated February 18, 1919, and my object is to improve the constructions employed for rotarily adjusting the hand on the arm member and for adjusting the hand to one side or the other of the axis of the arm member. It is more particularly my object to so design these parts that they are more easily and cheaply made while possessing equal or greater efficiency than the parts they replace.

I attain my object by means of the constructions hereinafter described and illustrated in the accompanying drawings in which

Figure 1 is an elevation of my improved hand connected to an artificial arm member;

Fig. 2 a similar view, partly in section, taken at right angles to Fig. 1;

Fig. 3 a longitudinal section of the connection between the hand member and the arm member;

Fig. 4 a plan view of the end plate and adjusting plate of the arm member;

Fig. 5 a partial longitudinal section on an enlarged scale of the connection between the hand and arm members; and

Fig. 6 a view similar to Fig. 5 showing a slight modification.

In the drawings like numerals of reference indicate corresponding parts in the different figures.

1 is an artificial arm member of ordinary construction adapted to be laced to a stump. The end of the arm member is formed by a flat metal plate 2, to which the hand member is connected. The hand member is provided for the purpose with a boss 3 having a threaded hole formed therein adapted to screw on to the threaded upper end of the pin 4. This pin 4 has a head 5 formed at its lower end and is rotatable in the end plate 2. On the end plate is superimposed an adjusting plate 6, which has a flat sided hole 7 formed therein (see Fig. 4) which engages a correspondingly shaped part 8 of the pin 4. The adjusting plate will thus serve to

rotate the pin 4 in the plate 2, while the plate 2 is itself free to slide sufficiently longitudinally of the pin to permit the boss 3 to be screwed down tight on the end of the pin 4 to jam the adjusting plate and the end plate together. The threaded end of the pin 4 is somewhat larger than the remainder of the pin so that the pin remains in position in the plates 2 and 6 when the boss is unscrewed.

The purpose of this construction is to enable the hand member to be rotarily adjusted on the arm member. It will be observed that when the boss 3 is clamped in place, it always assumes a certain position relative to the plate 6, so that by turning the plate 6 (when the parts are loose) to any desired position, the position of the hand member will also be found to be changed when it is screwed tightly in position.

I find it preferable to provide frictional means tending to resist the turning of the adjusting plate 6 on the end plate 2. For this purpose I may provide what is commonly called click mechanism, as shown in Fig. 5, or plates 9 of fiber or other frictional material as shown in Fig. 6.

In Figs. 3, 4 and 5 I show a spring actuated ball 10 supported by a holder 11 to operate through an opening in the end plate 2. A plurality of small holes 12 are formed in the adjusting plate 6 concentric with the pin 4 and in position to consecutively engage the ball 10. The ball, when engaging a hole, yieldingly resists movement of the adjusting plate, while the sound of the click indicates to the user when the plate has been adjusted through an angle corresponding to one or more holes. A lug 13 is provided on the adjusting plate to facilitate its rotary adjustment.

The boss 3 is provided with the jaws 14, between which is pivoted the shank 15 of the hook 16. The hook is thus adapted to swing on an axis at right angles to an axis longitudinal of the arm on which the boss 3 turns. It will be noted that the axis on which the shank is pivoted lies substantially in the same plane as the hook. The pivot pin on the shank passes through both jaws 14 and the shank and is suitably set up with a nut.

To adjust the angle of the hook as indicated particularly in Fig. 2, I provide a latch 18 pivoted in a slot formed in the shank 15 and adapted to engage any one of the notches 19 of a quadrant formed on one

of the jaws 14. A spring 20 engaging the latch and the shank provides means tending to hold the latch in engagement with the notches.

5 The hook is constructed substantially as in the prior patent hereinbefore referred to. The hook is double and the parts of each half remote from the shank are substantially arc-shaped as shown. The center from 10 which the arc is struck is located in the shank, preferably near the outer end thereof.

Between the halves of the hook is pivoted a clamp arm 21, which is preferably formed of resilient metal and is curved in the direction of its length as shown. To adjustably connect the clamp arm to the arc-shaped parts of the hook, I provide a dog 22 pivoted on the clamp arm and normally pressed by a spring 23 to engage the teeth of a rack 24, preferably a ratchet rack, formed in the outer side of the arc-shaped part of each half of the hook. The arm is thus easily swung to press against the outer side of any object with which the hook may be engaged and 25 releasably held as moved.

What I claim as my invention is:

1. The combination of a hand provided with a boss for attachment to an artificial arm member; jaws formed on said boss; a 30 hook member having a shank fitted between said jaws; a pivot pin passing through said jaws and shank, the shank above the pivot

pin being divided or slotted; a latch pivoted in the shank, a notched quadrant being formed on one of the jaws with which said latch is adapted to engage; and a spring engaging the latch and the shank tending to retain the lever in any one of the notches in the quadrant with which it is engaged.

2. An artificial arm member provided at 40 its end with a flat plate; a central pin rotatably connected with said plate and provided with a threaded outer end; an adjusting plate superimposed on the end plate, said adjusting plate being loose on but having a 45 rotative engagement with the pin; and a hand member provided with a boss adapted to screw on the pin and jam the adjusting plate and end plate together.

3. An artificial arm member provided at 50 its end with a flat plate; a central pin rotatably connected with said plate and provided with a threaded outer end; an adjusting plate superimposed on the end plate, said adjusting plate being loose on but having a 55 rotative engagement with the pin; a click device yieldingly retaining the adjusting plate in any predetermined position to which it is turned; and a hand member provided with a boss adapted to screw on the pin and jam the adjusting plate and end plate together.

Signed at the city of Toronto this 19th day of Feb., 1919.

BARTHOLOMEW BOWLER.
